(57) **CLAIM**

We claim the ornamental design for an A-frame cart, as shown and described.

DESCRIPTION

FIG. 1 is a perspective view showing an embodiment of our new design for an A-frame cart;

FIG. 2 is a left side view showing our new design shown in FIG. 1;

FIG. 3 is a right side view showing our new design shown in FIG. 1;

FIG. 4 is a top view showing our new design shown in FIG. 1;

FIG. 5 is a bottom view showing our new design shown in FIG. 1; and,

FIG. 6 is a front view showing our new design shown in FIG. 1, the back view being identical.

The portions shown in broken lines are not part of the claimed design but show the environment in which the design is associated.
